UNITED STATES PATENT OFFICE.

EVALD J. ENGMAN, OF JERSEY CITY, NEW JERSEY.

SUPPLY-VALVE FOR CANDLE-MAKING MACHINES AND SIMILAR DEVICES.

1,006,739.

Specification of Letters Patent. Patented Oct. 24, 1911.

Application filed January 30, 1911. Serial No. 605,382.

To all whom it may concern:

Be it known that I, EVALD J. ENGMAN, a citizen of the United States, residing at Jersey City, county of Hudson, and State of 5 New Jersey, have invented a new and Improved Supply - Valve for Candle - Making Machines and Similar Devices, of which the following is a specification.

This invention relates to a valve of novel 10 construction which is more particularly adapted to be used as a supply valve for controlling the conveyance of liquefied or similar readily flowing material into split molds, where such material is solidified. 15 Such a device is used for instance in machines for making candles, soap cakes, or similar articles. The valve is so constructed that a permanent tight joint is provided between the foot of the valve and the contacting 20 face of the mold, and that small irregularities occasioned in mounting or by wear are compensated for.

In the accompanying drawing: Figure 1 is a vertical section through the valve, showing 25 it applied to a candle making machine; Fig. 2 an enlarged longitudinal section through the valve and adjoining parts, and Fig. 3 a cross section on line 3—3, Fig. 2.

The numeral 10 indicates a tank below the 30 sloping bottom 11 of which is arranged a heating chamber 12 that maintains the casting material contained in tank 10 in a liquefied state. From bottom 11 depends an integral cylinder 13 which is surrounded by 35 the heating chamber and constitutes a valve casing. Bottom 11 is provided with an opening 14 concentric with cylinder 13 but of a diameter less than that of the cylinder, thereby forming a seat for a spring 15. Into 40 the lower threaded end of cylinder 13 is tapped a correspondingly threaded sleeve 16 having a lower contracted or tapering section 17. The latter has a central bore 18 which snugly embraces the upwardly extending cylindrical flange 19 of an annular 45 plate or foot 20. Between the flat bottom of sleeve section 17 and plate 20 is interposed a gasket or resilient member 21 that tends to force said plate against the upper faces of 50 a pair of mold blocks 22 forming jointly a candle casting recess 23. For permitting the ready removal of the finished candles, mold blocks 22 may be simultaneously reciprocated in opposite directions by suitably 55 actuated shipping rods 24.

Plate 20 extends inwardly beyond flange

19 to form a conical valve seat 25. The latter is adapted to be engaged by a correspondingly shaped valve plug 26, the lower face 27 of which is flush with the lower face 60 of plate 20 when the valve is closed (Fig. 2). From plug 26 extends upwardly a stem 28, the diameter of which is less than that of opening 14 to permit an unobstructed passage for the molten material. Near its lower 65 end, stem 28 is provided with a disk 29, the diameter of which is slightly less than the inner diameter of sleeve 16, so that the disk is freely reciprocable in the sleeve to constitute a guide for plug 26. Disk 29 is provided with a pair of opposed apertures 30 which permit the passage of the casting material. Spring 15 rests upon disk 29 and tends to lower plug 26 and thereby close the valve. Plug 26 and stem 28 are axially perforated for the accommodation of a wick 31. At its upper threaded end stem 28 carries a pair of adjusting nuts 32 which operatively connect the stem to a vertically reciprocative member 33 that may be actuated in 70 any suitable manner for raising and lowering stem 28 and to thus either open or close the valve.

It will be seen that by the means described, a valve of simple construction and 85 containing a minimum number of parts is obtained. The cushion 21 forces plate 20 against the mold so that an escape of the molten material is effectively prevented irrespective of wear and of slight irregularities 90 in the moving parts.

I claim:

1. In a device of the character described, a cylinder, a sleeve tapped therein and having a perforated tapering lower section, a 95 flanged annular plate engaging said section, a flexible gasket between the tapering sleeve section and plate, a valve seat formed on said plate, and a valve plug adapted to engage said seat.

2. In a device of the character described, a cylinder, a sleeve tapped therein and having a perforated tapering lower section, a flanged annular plate engaging said section, a flexible gasket between the tapering sleeve 105 section and plate, a valve seat formed on said plate, a valve plug adapted to engage said seat, a stem on said plug, and an apertured guide disk carried by the stem and accommodated by the sleeve.

3. In a device of the character described, a cylinder having an upper perforated spring

100

seat, a sleeve tapped into said cylinder and having a perforated tapering lower section, a flanged annular plate engaging said section, a flexible gasket between the tapering 5 sleeve section and plate, a valve seat formed on said plate, a valve plug adapted to engage said seat, a stem on said plug, an apertured guide disk carried by the stem and accommodated by the sleeve, and a spring 10 engaging said disk and said spring seat.

4. In a device of the character described, a cylinder, a sleeve tapped therein and having a perforated tapering lower section, a flanged annular plate engaging said section, 15 a flexible gasket between the tapering sleeve section and plate, a valve seat formed on said plate, a valve plug adapted to engage said seat, and having a flat bottom which is flush with the lower face of the plate when 20 the valve is closed.

5. In a device of the character described, a cylinder having an upper integral perforated spring seat, a sleeve tapped into said cylinder and having a perforated tapering lower section, an annular plate having a 25 cylindrical flange which is snugly embraced by said section, a flexible gasket between the tapering section and plate, a valve seat formed on said plate, a plug adapted to engage said seat, a stem on the plug, 30 the diameter of which is less than that of the spring seat perforation, an apertured guide disk carried by the stem and accommodated by the sleeve, and a spring interposed between the upper seat and the guide 35 disk.

EVALD J. ENGMAN.
